His Attorney.

UNITED STATES PATENT OFFICE

2,131,414

SPRING ACTION FRICTION BLOCK STRUCTURE

Arthur E. Westburgh, Jamestown, N. Y.

Application October 10, 1936, Serial No. 105,114

4 Claims. (Cl. 64—31)

This invention relates to a spring action friction block structure for flexible couplings, particularly of the general type having driving and driven coupling sections provided with lugs coupled by a friction block, and especially of the improved type disclosed in Letters Patent No. 2,007,513, issued to me on July 9, 1935, and it aims to provide such a spring action friction block structure as will take up the back lash between the four coupling jaws by uniform spring action.

It is further aimed to provide such a block in the nature of sections having intervening expansive coil springs which urge them to and maintain them in an operative position.

Another object is to provide a block of the present character from a plurality of block sections, preferably two triangular sections with spring means expanding them at their diagonal edges.

In addition I aim to provide such a block structure wherein the sections have removable friction shoes to contact the lugs of the coupling, the spring feature rendering it easier to remove and replace the shoes, and to provide a novel lubricating means in coaction with said shoes.

The more specific objects and advantages will become apparent from the description following taken in connection with accompanying drawing illustrating an operative embodiment.

In said drawing:

Figure 1 is a view in perspective showing the improved spring friction block structure, partly broken away to disclose details;

Figure 2 is a detail perspective view of one of the shoes or friction strips alone;

Figure 3 is a transverse sectional view taken through a coupling employing my invention;

Figure 4 is a longitudinal sectional view taken on the plane of line A—A of Figure 3, and

Figure 5 is a detail perspective view of a coupling employing my invention, the parts being partially assembled.

Referring specifically to the drawing wherein like reference characters designate like or corresponding parts, the improved friction block structure is shown in Figure 1. It employs a plurality of sections 10, preferably two, which are right triangular and face at their hypotenuses or diagonal edges 11. Recesses 12 are bored in said edges and removably accommodate expansive coil springs 13 which urge said edges 11 apart as shown in Figure 1.

The right angular edges of the sections 10 are equipped with removable shoes or friction strips 14. Said shoes or strips may be made from any

desired friction material, such as that from which brake shoes are made, especially their molded lining, and for instance from a phenolic condensation product or bakelite having a textile fiber base, such as the specific material sold under the name of Micarta.

Said shoes or strips 14 are secured to the sections, for example, by set screws 15, countersunk into the shoes, and engaging screw threads in recesses 16 in the sections. Such sections 10 may to advantage be constructed of metal.

In the right angular faces of the sections 10 are reservoirs, cavities or recesses 17 which may contain graphite or other lubricant. Said reservoirs are spanned by the shoes and are capable of being filled with the lubricant when the shoes are removed. Such lubricant exudes or escapes from the reservoirs through ports or openings 18 provided through the shoes in communication therewith.

The friction coupling of my Patent No. 2,007,513 is an example of one form in which the improved spring action friction block structure may be employed to advantage. Such a coupling is generally shown in Figures 3 to 5 and it employs similar coupling sections A, one of which is adapted to be rigidly fastened to a driving shaft and the other of which is adapted to be rigidly fastened to a driven shaft, as disclosed in said patent. Removable jaws A' conform to the jaws of the patented structure as they provide two lugs B on each coupling section, the lugs of one section being arranged at a right angle to the lugs of the other section.

The spring action friction block is operatively positioned between the coupling sections A, enclosed by the lugs B with the inner planar surfaces thereof frictionally contacting with the outer surfaces of the adjacent shoes 14, the degree of friction being augmented and controlled by the tension of the springs 13. Such planar surfaces and engaged surfaces of the shoes 14 will be efficiently lubricated by the lubricant exuding from the ports 18. It will be realized too that the lugs B of each coupling section engage parallel shoes of different block sections 10. Obviously any desired number of the springs 13 may be employed and it will be noted that their tension is exerted in four directions so as to uniformly take up the back lash between the coupling jaws or lugs in the operation of the coupling.

Various changes may be resorted to provided they fall within the spirit and scope of the invention.

I claim as my invention:

1. In a friction block for contact with the surrounding jaws of the sections of a flexible coupling, said block at its jaw-engaging edges having removable shoes, said block comprising metallic sections provided with diagonal faces, said faces having recesses therein, and expansive coil springs seated in said recesses.
2. In a friction block for contact with the surrounding jaws of the sections of a flexible coupling, edges of said block being dished in spaced relation to the margins to provide lubricant reservoirs, ported shoes of friction material directly engaging said edges and covering said reservoirs, said shoes being in continuous engagement with the edges around the reservoirs with the ports forming outlets for the reservoirs.
3. In a friction block for contact with the surrounding jaws of the sections of a flexible coupling for two shafts, said block comprising metallic sections provided with diagonal meeting faces,

expansive spring means constantly urging each block section into contact with angularly arranged jaws of each coupling section, said faces being recessed to seat said spring means.

4. In a friction block for contact with the surrounding jaws of the sections of a flexible coupling for two shafts, the block comprising two triangular sections substantially similar in size facing each other at their diagonal edges, and spring means constantly expanding the block sections away from said edges on a line perpendicular to said edges and each block section into contact with angularly arranged jaws, one on each coupling section, edges of the block section being dished in spaced relation to the margins to provide lubricant reservoirs, and shoes of friction material having outlet ports for the reservoirs directly covering said reservoirs and engaging said edges continuously around said reservoirs.

20

ARTHUR E. WESTBURGH.
